UNITED STATES PATENT OFFICE.

CLEMENT G. HARRINGTON, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

DUMPING-CAR.

1,066,728.

Specification of Letters Patent.

Patented July 8, 1913.

Original application filed August 23, 1910, Serial No. 578,592. Divided and this application filed August 21, 1912. Serial No. 716,122.

To all whom it may concern:

Be it known that I, CLEMENT G. HARRINGTON, residing at 915 Olive street, St. Louis, Missouri, and being a citizen of the United States, have invented certain new and useful Improvements in Dumping-Cars, of which the following is a full, clear, and exact description, such as will enable others skilled in the art to which it appertains to make and to use the same.

This application is a divisional application of Serial No. 578,592 filed August 23rd, 1910, reference being had to the accompanying drawings which illustrate the preferred form of the invention; though it is to be understood that the invention is not limited to the exact details of construction shown and described, as it is obvious that various modifications thereof will occur to persons skilled in the art.

In said drawings: Figure 1 is a view in side elevation of one-half of a car embodying the features of the present invention, the undisclosed half being a duplicate of that disclosed. Fig. 2 is a transverse, vertical section taken on the plane indicated by line 2-2 of Fig. 1. Fig. 3 is a longitudinal, vertical, fragmentary section taken on the plane indicated by line 3-3 of Fig. 2, and looking in the direction indicated by the arrow. Fig. 4 is an inverted plan view of one half of the car showing the hoppers with the door operating mechanism therefor. Fig. 5 is a detail hereinafter described.

This invention relates to improvements in steel hopper cars, and particularly to such as are provided with lever actuated dumping valves.

Among the objects in view are simplicity and efficiency of manipulation of the operating parts as well as the effective distribution of strains.

Referring to the drawings by numerals, 1, 1 indicates the longitudinal plates of the center sill, and 2, 2 the side girders, which latter form the sides of the car.

The car may be divided into as many hoppers as preferred, but for the purpose of illustration the car is indicated as being provided with four hoppers, two being arranged side by side in each half-length of the car, and each hopper consisting of the respective side or side girder 2, and front and rear inclined floors 3 and longitudinally extending

laterally inclined floors, 4, 4. Each side girder 2 depends below the outer floor 4 of the respective hopper, and intermediate of the length of said floor are arranged castings 5-5, spaced apart and each riveted to the side girder 2 and extending to and affording a support for the inclined floor 4. Each casting 5 preferably consists of a hollow casing, made up, as best seen in Fig. 5, of side plates 5' and a connecting cross web 5'' extending along the inner inclined edges of the plates 5' along the upper horizontal edges thereof, and down along the outer edges thereof, the inner lower edges being left disconnected, and the said web 5'' receiving the rivets with which the casting or casing 5 is connected to the side girder 2. Each plate 5' of each casing 5 is formed at its upper inclined edge with a notch 6, producing an ear 7, and these two ears of each casing are perforated for receiving a pintle or hinge bolt 8. The center plates 1 are connected at their upper edges by cross webs or plates 9-9 extending downwardly between the sill members and united thereto. Upon the webs 9-9 is arranged a V shaped cover plate 10 riveted or otherwise suitably secured to the plates 9 and having its opposite legs extending downwardly across the upper edges of the center sill plates 1-1 and forming the inner inclined floor 4 of the adjacent hopper. The upper edge of each plate 1 is provided an angle bar 11 riveted to the plate 10, said angle having outstanding horizontal flange. Between each of the plates 1 and the contiguous floor 4 are arranged castings or casings 5^a, constructed exactly like the casings 5, and riveted to the plate 1 and extending to and supporting the contiguous floor 4. The floors 4 terminate a considerable distance above the bottom central point of respective hoppers and the remaining portion of each hopper is completed by a pair of valves or doors 12, one being pivotally carried by the pintles 8 of the casings 5, and inclining, when closed, downwardly and inwardly, to the bottom central point of the hopper, and the other being pivotally carried by the pintles 8 of the casings 5^a and inclining, when closed, downwardly and outwardly to the lower edge of said first door.

Each door 12 overlaps the respective floor 4 and is provided about all of its edges with a downwardly extending flange 13 ly-

ing, when the door is closed, within the notches 6, at the upper edges of said doors. A pair of hinge straps 14—14, riveted to the under side of each door are designed to engage the pintles 8—8 in the casings 5 and 5^a for pivotally sustaining the door in engagement with the pintles, each strap 14 extending between the pair of side plates 5' of the respective casing carrying the given pintle 8. Obviously, as many of the casings 5 and 5^a and hinge straps 14 may be provided as desired, but a pair for each door is usually sufficient. The flange 13 along the lower edge of each door 12, is preferably formed with a downwardly turned bend 13' adapted to snugly fit a correspondingly shaped portion of a pressing 15 extending throughout the length of and centrally beneath the open bottom of each hopper, and terminating at its ends in end flanges 16, 16, riveted to the depending cross plates or bulk heads 17 at the ends of the open bottom of the hopper. The conformity of flange 13 with the transverse angular form of the pressing 15 insures a snug, close fit of the doors 12, providing against springing of the parts or other openings affording opportunity for leakage.

Each door is supported in its closed position by a pair of bell crank levers 20, 21 carrying, at their ends next the doors shafts 19 on which are supported rollers 18 bearing against the outer or under faces of the doors. Each bell crank is pivotally supported, the pivot comprising preferably a fixed pin as 22 projecting from a suitable bracket 22^a carried by the respective bulk head 17.

The bell crank levers 21—21, carrying rod 19 for the outer door 12, are continued, in the form of flat bars 23, and the outer ends thereof project beyond the side girder 2 and are twisted, as at 24, for presenting their flat faces toward the outer face of the girder. These levers are connected together by a tie rod 23^a. The extensions 23 are bent approximately at the point of the twist 24 for producing an angular portion adapted to extend, when the doors are in closed position, about the horizontal flange of the angle bar 2' of girder 2. The outer ends of the extensions 23 are preferably slotted and adapted for engagement with locking members 25—25 projecting outwardly from the side face of the side girder 2. The locking members extend through the slots and suitable cotter pins 26 retain the levers in raised position. It is to be noted that when the parts are in closed position, the shaft 19 is in that alignment with the pivots 22, commonly known as a dead center, so that the pressure exerted on each of the doors 12 will be taken up directly by the pivots 22 with no appreciable pressure on the outer portions of the levers 21, such pressure be-

ing taken up as a direct longitudinal stress by the short arm 20.

The free arm of each inner lever 21 is pivotally engaged by a depending link 27, said link at its lower end pivotally engaging a slide bar 32, a rod 28 being provided for and connecting the links 27 of the pair of inner levers 21 for each inner door 12. The inner ends of bars 32 are fixed to slides 29 carried on and engaging ways 30, each slide having an upper and a lower flange lapping the upper and lower edges of their respective way 30. A similar slide 31 slidingly engages each way 30, and is spaced thereon outwardly from slide 29 and connected with slide 29 by the bar 32, said bar being bent or otherwise constructed at its outer end to form an operating handle or grip 33. When the door is closed the links 27 extend substantially vertically above the rod 28, thus practically locking the connected levers 21 against rotation. Near the outer end of each bar 32, the same is formed with an aperture 32' registering when the door 12 is closed, with a corresponding opening 30' formed in way 30, through which registering openings is passed a removable key or other suitable locking device 32" for locking the bar 32 and more effectually retaining the parts in a closed position. Each bar 32 may be of any desired length, and each link 27 is preferably of a length for causing the rod 28 to lie beneath pressing 15 when the inner door 12 is open, as seen at the left end of Fig. 2. Each way 30 is braced and supported by stays and braces 34, 34, extending downwardly from parts of the car body, and each way 30 preferably consists of a flat strip which extends across the entire width of the car, so as to serve as a way for the slide of the inner door 12 of each of the hoppers of the laterally juxtaposed pair.

For guiding and enabling forcible opening of the doors, when frozen or otherwise stuck in closed position, by movement of bars 19, each of said bars extends through and travels transversely within a pair of guiding brackets 35 fixed to the respective door 12. At the lower terminus of movement of each bar 19, the outstanding flange or web of an angle plate 36 is arranged, said angle plate being comprised in the bracket 35, so that the bar is sustained against excess downward movement. Obviously, as many brackets 35 may be provided as desired but two such brackets spaced apart along the door are usually sufficient for each rod 19.

It is to be observed that each hinge casing 5 has its attached edge comparatively long and lapping and riveted to the vertical flange of the contiguous edge angle 2' of the respective sill or side girder. The stress of the load is thus distributed from 120

the hinges directly to the sills almost entirely as a downward component and with but a minimum of lateral or bursting strain. Obviously, while the means of attachment for various parts has been herein mentioned as rivets, and while such specific means is preferred, any of the known methods of attachment may be utilized within the spirit and intent of the invention.

10 The shifting connection between the respective doors and their operating bell crank levers, and the directness of engagement of the levers with the doors, insures ease and certainty of operation. Either door 12 of any hopper may be manipulated independently of the other, whereby the entire load may be discharged near the center of the car, by opening only the inner doors, or approximately one-half of the load may be discharged at each side of the car, by opening only the outer doors, or the load may be discharged directly downwardly by opening all of the doors simultaneously. The simultaneous opening of both doors of one hopper uncovers the openings in the bottom of that hopper, as indicated at the left of Fig. 2, and its load can thus be practically instantly discharged. To close the outer doors, it is only necessary to lift the projecting ends 23 of outer levers 21 into engagement with locking members 25, which lifting movement, causing travel of rollers 18 along the under side of the door, will swing said door closed, and the retaining pins 26 may be positioned for locking the parts closed. To open said door requires only the removal of the pins 26 and the starting of the outer ends of the levers downwardly for moving bar 19 from the line of dead center, whereupon the door will be released and will open by reason of the weight of the sustained load or may be forced open by engagement of the rod 19 with the guides 35. The action of the inner set of levers, for operating the inner door 12, is the same as that just described, except that the slide bars 32 are shifted longitudinally in lieu of the swinging movement of the outer ends of the outer levers, the links 27 transmitting movement from slide bars 32 to the inner levers 21.

What I claim is,

1. In a dumping car, the combination with a car body and a dumping door therefor hinged thereto, of a bell crank lever pivotally supported beneath the door having one of its arms extending upwardly into engagement with said door, and having its other arm formed with an operating handle extending beyond the hinge of said door.
2. In a dumping car, the combination with a car body and a dumping door therefor hinged thereto, of a bell crank lever adapted to control and actuate said door, one arm of said lever extending beyond the side

of the car, and means for engaging and locking said arm against movement.

3. In a dumping car, the combination with a car body having a side girder provided with a lower edge flange, and a dumping door having a hinged connection with said car body, of a bell crank lever pivotally supported contiguous to said door and adapted to manipulate and control the door, one arm of said lever extending beyond the side girder and being bent intermediate its length for extending about the said edge flange, and means sustained by the girder for locking the outer end of said arm in a given position.

4. In a dumping car, the combination with a car body and a dumping door therefor hinged thereto, of a pair of bell crank levers pivotally supported independently of the door, a rod connecting one arm of one of said levers with one arm of the other lever, a bearing carried by said rod and engaging the door, and a bar connecting the other arms of the levers.

5. In a dumping car, the combination with a car body and a dumping door therefor hinged thereto, of a pair of bell crank levers pivotally supported independently of the door, a rod connecting one arm of one of said levers with one arm of the other lever, a guiding bracket carried by the door and extending about said rod, and means connecting the other arms of the levers.

6. In a dumping car, the combination with a car body and a dumping door therefor hinged thereto, of a pivot pin fixed to said car body, and a bell crank lever rotatably carried on said pivot pin having one of its arms extending into connection with the door and having its other arm formed with an operating handle for manipulating said door.

7. In a dumping car, the combination with a car body and a dumping door therefor hinged thereto along one of the sides of said door, a pivot pin fixed to said car body, a bell crank lever rotatably carried on said pivot pin, said pin and bell crank lever being disposed at one end of said door out of the path of movement thereof, means carried by one arm of said lever extending beneath and engaging said door, and the other arm of said lever being formed with an operating handle for manipulating said door.

8. In a dumping car, the combination with a car body and a dumping door therefor hinged thereto, of a bell crank lever pivotally connected at its angle to the car body and having one arm provided with direct connections with the door, said car body comprising a side girder and said bell crank lever having its other arm formed with an operating handle adapted to be moved into locked relation with the outer surface of said side girder.

9. In a dumping car, the combination with a car body and a dumping door therefor hinged thereto, of a pair of bell crank levers pivotally sustained by the car for manipulating said door, said car body comprising a side girder and said bell crank levers being formed with operating handles adapted to be moved into locked relation with said side girder. 60
10. In a dumping car, the combination with a car body and a dumping door therefor hinged thereto along one of the sides of said door, a pair of bell crank levers disposed one at each end of the door being spaced from the path of movement thereof, means extending between and connecting said levers beneath said door, door engaging means carried by said connecting means, and an operating handle formed upon each 65 of said bell cranks. 70
11. In a dumping car, the combination with a car body and a dumping door therefor hinged thereto along one side of said door, a pair of bell crank levers for operating said door disposed one at each end of the door being spaced from the path of movement thereof, means extending between and connecting said levers beneath said door, and an operating handle formed upon 75 each of said bell cranks. 80
12. In a door operating device, the combination comprising a hinged door, a lever having an actuating handle, a stop for limiting the movement of said lever in one direction, and means for engaging said handle for locking said door while said lever is in engagement with said stop. 85
13. In a door operating device, the combination comprising a door, an actuating lever, a stop for limiting the movement of said lever in one direction, means for engaging said lever for locking said door while said lever is in engagement with said stop, and means engaged by said lever when said 90 lever is out of engagement with said stop for forcing the door open. 95
14. In a hopper door operating device, the combination comprising a drop door, a side girder, a locking means comprising a bell crank lever rockable on a fixed pivot, one of its parts adapted to engage the door and the other part adapted to be locked to the girder to hold said door in locked position. 100
15. In a hopper door operating device, the combination with a car side, of a drop door, means for actuating and locking said door, said means comprising a single member in the form of a manually actuated bell crank lever having a part extending to the outside of said car side. 105
16. In a hopper door operating device, the combination with a car side, of a drop door, means for actuating and locking said door, said means comprising a single member in the form of a bell crank lever, one arm of 65 said lever engaging the door and the other arm of said lever constituting an actuating handle and part of a locking means disposed on the outside of the car side. 110
17. In a door operating device, a door, a side girder, a lever movable with said door extending laterally of the said girder and means fastening said lever to the outside of said girder. 70
18. In a door operating mechanism, a hopper bottom, a door, means slidably mounted beneath and positively engaging said door, spaced levers engaging opposite ends of said sliding means, one of the arms of each of 75 said levers constituting an actuating handle. 80
19. In a door operating mechanism, a hopper bottom, a door, means slidably mounted beneath and positively engaging said door, spaced levers engaging opposite ends of said sliding means, one of the arms of each of 85 said levers constituting an actuating handle, and means connecting said handles. 90
20. In a hopper bottom car, the combination of a side girder having a lower angle bar, a casting mounted on said girder, a drop door pivoted to said casting, a bell crank lever having a fixed fulcrum, one arm of said lever engaging the door to actuate the same, the other arm of said lever adapted to fit about said angle bar to engage 95 said girder when said door is in closed position. 100
21. In a hopper bottom car, the combination of a side girder having a lower angle bar, a casting mounted on said girder, a drop door pivoted to said casting, a bell crank lever having a fixed fulcrum, one arm of said lever engaging the door to actuate the same, the other arm of said lever adapted to fit about said angle bar to engage 105 said girder when said door is in closed position, and a locking member carried by said girder adapted to fasten said bent arm to said girder. 110

In witness whereof I have hereunto set my hand in the presence of two witnesses.

CLEMENT G. HARRINGTON.

Witnesses:

JAMES J. COOPER,
OSCAR HOCHBERG.
